UNITED STATES PATENT OFFICE.

CHARLES A. SCHEIF, OF PITTSBURGH, PENNSYLVANIA.

WINDOW-SHADE PULL.

Application filed September 25, 1925. Serial No. 58,524.

This invention relates to window shade pulls and the primary object thereof is to provide an improved device of the character stated, which embodies novel means to facilitate its mounting in the secured position upon the stay of the window shade or its removal therefrom.

Further objects of this invention are to provide a device of the class specified, in a manner as hereinafter set forth, which is simple in its construction and arrangement, strong, durable and efficient in its use, compact, attractive in appearance and positive in its action, and comparatively inexpensive to manufacture.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawing forming a portion of this specification and wherein like numerals of reference designate corresponding parts throughout the several views:—

Figure 1 is a fragmentary rear view of a window shade and provided with a pull device in accordance with my invention.

Figure 2 is an enlarged rear view of the securing clip, illustrating the adaptation of the pendant as an operating element therefor.

Figure 3 is an enlarged front view of the securing clip.

Figure 4 is a vertical side view thereof.

Figure 5 is a bottom plan view of the securing clip.

Figure 6 is an elevation of the pendant disconnected.

Referring in detail to the drawing 1 denotes the body portion of the clip which is preferably constructed from spring metal bent into a substantially U-shaped form so as to conform to and receive the lower marginal edge of the wooden shade stay 2. The resiliency of the spring metal, from which the body portion 1 of the clip is formed, provides a gripping action for securing the clip in position to the stay 2, in the manner to be described.

The front leg 3, of the body portion 1, is formed with an aperture 4, adjacent to its upper end, and extends somewhat above the

rear leg 5, of the body portion 1, so that when being forced into position, the longer front leg 3 will contact first with the shade stay 2 and facilitate a spreading movement of the body portion 1.

The upper end of the rear leg 5 is provided with a tooth 6, which extends toward the front leg 3, and is designed to enter through the shade material and insert itself in the wooden shade stay 2, whereby the clip is securely retained in position.

When the clip is detached from the shade its resilience will tend to draw the upper ends of the front leg 3 and rear leg 5 toward each other, as clearly as shown in Figure 4, of the drawing. The aperture 4, formed in the front leg 3, will allow the tooth 6 to project therein, thus preventing entanglement when a number of the clips are placed together during the process of formation, finish or transportation.

Formed in the front leg 3, of the body portion 1, is an enlarged opening 7, the lower edge of which communicates with a slot 8. This slot continues down to the bottom of the body portion and at that point communicates with a small centrally disposed opening 9 formed in the pocket 14'.

A flexible operating member, preferably consisting of a bead ball chain 10, as illustrated, is attached to the clip by inserting the ball at the upper end of the chain 10 through the enlarged opening 7 and drawing the connecting link downward through the slot 8 until the said ball at the upper end of the chain 10 is seated in the pocket 14', in which position the connecting link will project through the small opening 9 and suspend the chain 10 perpendicularly therefrom, as clearly shown in Figure 1, of the drawing. The rear leg 3 is formed with a pair of opposed ears 8, which extend into the upper end of the slot 8 to prevent the disengagement of the chain 10 therefrom.

The rear leg 5 is formed, adjacent to its upper end, with a round aperture 11 and with a triangular aperture 12, disposed approximately at the center thereof. The aperture 11 and the aperture 12 are provided for the purpose of permitting the insertion of a suitable implement to facilitate the spreading of the legs 3 and 5 when attaching the clip to the shade stay 2, in the manner hereinbefore described.

The upper end of the front leg 3 extends above the upper end of the rear leg 5, and

provides a purchase for engaging the front side of the shade stay 2 for facilitating the attachment of the body portion 1 to the latter.

The body portion 1 increases in width toward the bottom thereof, and the latter, adjacent to each end, is provided with an upwardly extending cut out portion 13 for the purpose of providing the desired bottom formation, establishing the proper resiliency of the clip, and further to enhance the general appearance and ornamentation of the device.

The central bottom portion 14, of the body portion 1, extends somewhat below the bottom ends 15. This formation of the bottom together with the pocket 14' formed in the bottom portion 14, permits of the close engagement of the ends 15 with the lower edge of the shade stay 2 when the bead chain 10 is connected in the central bottom portion 14, in the manner hereinbefore described.

The bead ball chain 10 carries a hand-hold pendent 16 which is attached adjacent to the lower end thereof. The pendent 16 is preferably constructed from sheet metal and is formed with a tapering lower end 17. While serving as a hand hold for adjusting the shade, the pendent 16 is also adapted to be utilized as an implement, to engage the round opening 11 or the triangular aperture 12 to facilitate the spreading apart of the legs 3 and 5 when attaching the clip to the marginal lower edge of the window shade stay 2, or when it is desired to remove the clip from the latter.

The pendent 16 is formed with a circular upper portion 18 provided with an opening 19. A slotted cap 20 is formed on top of the

portion 18 and is adapted to engage the chain 10 adjacent to the end thereof. An enlarged ball 21 is carried on the extreme lower end of the chain 10 to allow its suspension centrally of the opening 19 formed in the circular portion 18 of the pendent 16 and provides ornamentation and a hand hold when the pendent 16 is not used.

From the foregoing description taken in connection with the accompanying drawing, the principle of construction and the method of operation will be readily apparent to those skilled in the art to which the invention appertains, and while describing what is now thought to be the best embodiment thereof, it is to be understood that the device shown in the drawing is merely illustrative, and that various changes in the form, proportions and minor details of construction may be resorted to without departing from the principle or sacrificing any of the advantages of the invention, which come within the scope of the claim hereunto appended.

What I claim is:

In a window shade pull of that type including a clip element having long and short clip members, a pendant constituting a handhold and formed of an upper circular part having an aperture and a lower tapered part adapted to engage in said short clip member to facilitate the attachment or removal of said element to and from the shade, the upper portion of said pendant formed to provide a slotted cap, and a flexible member connecting with said slotted cap and with said clip element for suspending said pendant from the latter.

In testimony whereof I affix my signature.
CHARLES A. SCHEIF.
